Primary Examiner — Robin V Webster*Assistant Examiner* — Keith J Wilson(74) *Attorney, Agent, or Firm* — Daryl R. Wright; Greg Carr(57) **CLAIM**

We claim the ornamental design for a tire for a model vehicle, as shown and described.

DESCRIPTION

FIG. 1 is a top, left, front perspective view of a tire for a model vehicle;

FIG. 2 is left side elevation view thereof;

FIG. 3 is a front elevation view thereof; and,

FIG. 4 is a top, left, front perspective view of a tire for a model vehicle mounted on a model vehicle platform. The broken line showing of the model vehicle platform is provided for the purposes of illustrating environmental structure and forms no part of the claimed design.

The broken lines depicting the interior of the tire illustrate portions of the tire for a model vehicle that form no part of the claimed design.
